UNITED STATES PATENT OFFICE.

JACOB H. PETERSON, OF MORELAND, IOWA.

MECHANICAL MOVEMENT.

SPECIFICATION forming part of Letters Patent No. 453,207, dated June 2, 1891.

Application filed August 4, 1890. Serial No. 361,009. (No model.)

To all whom it may concern:

Be it known that I, JACOB H. PETERSON, a citizen of the United States, residing at Moreland, in the county of Webster and State of 5 Iowa, have invented a new and useful Mechanical Movement, of which the following is a specification.

My invention relates to that class of mechanical movements especially designed for 10 propelling vehicles; and it has for its object the provision of means by which an energy of comparatively small intensity at the point of application may be made to reappear as an energy of comparatively considerable in- 15 tensity at the point of application, in combination with means by which potential energy may be stored and utilized while the machine is at motion or at rest.

My invention consists, structurally, in a central drive-shaft within a suitable frame having double toothed perimeters, one of which meshes with the wheel mounted on a shaft, from which the movement of rotation may be communicated to the running-gear of the 25 vehicle, and the other engaged by pawls secured to the pivoted linking connections of a hand-lever, so that the central drive-wheel may be rotated in one common direction in the reciprocation of the lever, in combination with pawls and ratchets and particular constructions and arrangements by which a spring coiled about the central shaft may be wound while the machine is at rest or in motion and its potential energy stored to assist 35 in actuating the vehicle.

My invention consists, further, in pivoted pawls and ratchet-wheels which wind the spring fixed to the central drive-shaft during the operation of the machine.

My invention consists, further, in certain details of construction hereinafter more fully described, reference being had to the accompanying drawings, in which—

Figure 1 is a side view of my improved mechanism. Fig. 2 is a top plan view of the same. Figs. 3 and 4 are detail views illustrating the separable lever, spring, and spring-winding device. Fig. 5 is a side elevation of the central drive-wheel, one of the webs thereof being removed to show the spring. Fig. 6 is a sectional view of the central drive-wheel. Fig. 7 is a detail enlarged view showing the

pawl and ratchet for winding the spring. Fig. 8 is an enlarged detail cross-sectional elevation through the center of the drive-wheel. 55

A represents a supporting or carrying frame, which may be of such a form as to adapt it for use in conjunction with the particular form of vehicle to which it may be desired to apply the mechanism. 60

B represents a central drive-wheel fixedly mounted upon the drive-shaft B², said wheel having a double perimeter b b'.

C is a hand-actuated lever consisting of two parts c c', connected near their top portions 65 by means of a cross-piece c'', Fig. 4.

The central drive-wheel B, as shown in Figs. 5, 6, and 8, is made up of two webs e and e', one of which e is formed with the toothed perimeters b b', and the one e' adapted to be 70 adjusted and bolted to the web e after the spring H is adjusted and secured in place, as about to be described. Formed in two parts e'' and e''' is a central hub-wheel E⁴, keyed to the collar h, which said parts are bolted 75 together, one end of the convolute spring H being first secured to the pin h'. Both of the webs e and e' being perforated at their centers, the web e is first slipped over and upon the shaft B and adjusted in position 80 upon the flanges of the central hub E⁴, as shown more clearly in Fig. 8. The spring H is then disposed within the interior periphery of the perimeters b and b', as shown in Fig. 5, its remaining outer end being secured 85 to the pin h'', after which the remaining web e' is adjusted in place and bolted to web e, thus forming the completed wheel B, with the spring disposed within its interior, the said wheel B being mounted upon the shaft B², 90 fixed in the frame and free to rotate independently about the same and independently also of the collar h, except that in the case of the latter the central hub E⁴, being keyed to the collar h, mounted on the shaft B², is connected by the spring H to or near the periphery of the wheel B, said wheel, however, revolving entirely independently of the stationary shaft B².

Referring to Fig. 7, the means of winding 100 the spring is more clearly shown, in this instance but one ratchet-wheel J² being employed, secured to the collar h, which is the preferred form.

Pivoted between the two pieces D at their lower ends is a pawl D², which is kept in engagement with the ratchet-teeth of the perimeter of the rim b' by the spring d'.

5 D³ is a horizontal connecting-link pivotally connected to the lower end portions of the connecting-pieces D at one end and at the other pivotally connected to the vertical connecting-piece D⁴, the upper end of which latter is pivotally connected to the ends of horizontal connecting-pieces D⁵, the other ends of which latter are pivotally mounted about the axis B² of the central drive-wheel B. Between the connecting-pieces D⁵ is pivoted a 15 pawl D⁶, held in engagement with the perimeter b' of wheel B by means of spring d'.

D⁷ is an arm pivoted at one end to the point of junction between the horizontal connecting-link D³ and the vertical connecting-link 20 D⁴ and at its other end pivoted within the end of the frame A.

The perimeter b of the central drive-wheel B is formed with teeth, which mesh with those of a pinion E, mounted fixedly on the 25 shaft E², which latter finds its bearings within the frame A. The pinion E is fixed to a sprocket-wheel E³, also fixedly mounted on the shaft E². It is evident, however, that the wheel E³, being the last in the train of mechanism, may be of a character suitable for the 30 performance of the given work.

H is a convolute spring, which is disposed about and has one of its ends secured to a collar or sleeve h, loosely mounted in the 35 frame and adapted to be rotated in manner to be described. Through the central drive-wheel shaft B² passes the other end of the spring, being secured to the wheel B by means of a pin, (not shown,) the spring H in turn being secured to the pin, the lever C being 40 made up of two parts, one of which c' is adapted to be separated from the other c by a latch C², holding said part c' to the cross-piece c''. The separable part c' has secured 45 to its lower end check-plates J, which are mounted on collar h and hold pivoted between them a spring-pawl j, which engages the teeth of the ratchet-wheel J², fixed to said collar h. j' is a spring-dog, also engaging the 50 teeth of the ratchet J². J³ is a ratchet-wheel, also fixed to the collar h, engaged by the spring-pawl j'', which latter is pivoted on the connecting-piece D⁵.

The operation of my device is as follows: 55 The operator actuates the lever C through the medium of the connecting-pieces D, the horizontal connecting-link D³, vertical connecting-link D⁴, and horizontal connecting-pieces D⁵, the pawl D⁶ engaging the perimeter b' of and rotating the central drive-wheel in the one movement of the lever C, and the pawl D² engaging the perimeter b' of and rotating the said wheel in the same direction on the movement of the said lever in the op-

posite direction. By this means a practically 65 continuous rotation of the central drive-wheel B is obtained, which is transmitted to the sprocket-wheel E³.

In the actuation of the lever C the pawl j, 70 pivoted between the check-plates J, engages the ratchet-wheel J², fixed to the collar h, which latter in turn rotates the central hub E⁴, winding the spring H, this being accomplished in the backward movement of the lever C, which lever in its forward movement 75 causes the pawl J'' to engage and actuate its ratchet-wheel J², the dog j' serving to keep the spring H from unwinding.

If it be desired to wind the spring H when the machine is at rest, the operator may operate 80 the lever C by unlatching and disconnecting the part c', and said part through the medium of its pawl J, acting on ratchet-wheel J², may then be employed to wind the spring.

Having thus described my invention, what I 85 claim as new therein, and desire to secure by Letters Patent, is—

1. The combination, in a mechanical movement, of a central drive-wheel, a spring arranged about a sleeve, the latter having a 90 ratchet or plurality of ratchet-wheels fixed thereto, said spring being secured to the central drive-wheel to actuate the same, and pawls engaging the ratchet-wheels, said pawls being actuated to weld the spring in both movements of the actuating-lever, as and for the purposes set forth.

2. In a mechanical movement, a separable actuating-lever formed of two parts, a central drive-wheel, a plurality of pawls engaging the drive-wheel, connecting-links carrying said pawls actuated by one of the parts of said levers, a spring secured at one end to the central drive-wheel, a sleeve to which the other end of the spring is fixed, a ratchet-wheel carried by said sleeve, and a pawl or pawls engaging said ratchet-wheel, actuated by the other part of the lever to wind the spring when the machine is either in motion or at rest, as set forth.

3. In a mechanical movement, a central drive-wheel having double toothed perimeters, a plurality of connecting-links operated by a lever, a plurality of pawls engaging the perimeters of the central drive-wheels, operated by the lever, a convolute spring disposed within the central drive-wheel and having one of its ends fastened thereto, a rotatable sleeve mounted upon a stationary axis secured in the frame to which the remaining end of the spring is fixed, a ratchet wheel or wheels fixed upon said sleeve, and a pawl or pawls actuated by the lever, engaging said ratchet wheel or wheels, as set forth.

JACOB H. PETERSON.
